UNITED STATES PATENT OFFICE.

ALFRED M. DEMUTH, OF SAN FRANCISCO, CALIFORNIA, ASSIGNOR TO JOHN A. KELLY,
OF CHICAGO, ILLINOIS.

COOKER.

1,308,485.

Specification of Letters Patent.

Patented July 1, 1919.

Application filed September 18, 1916. Serial No. 119,857.

To all whom it may concern:

Be it known that I, ALFRED M. DEMUTH, a citizen of the United States, residing at San Francisco, in the county of San Francisco and State of California, have invented new and useful Improvements in Cookers, of which the following is a specification.

The object of the present invention is to provide an improved cooker by which edibles can be cooked entirely in their own juices and thereby retain their peculiar aroma and flavor. They will thus be of superior flavor and very tender, and will preserve their original form to a greater degree than before.

In the accompanying drawings, Figure 1 is a front view of my improved cooker; Fig. 2 is a transverse sectional view thereof; Fig. 3 is a longitudinal section on the line 3—3 of Fig. 2; Fig. 4 is a broken sectional view showing a cooking vessel extended.

Referring to the drawing, 1 indicates a rectangular boiler, in the front wall 2 of which are rectangular openings, around 25 which are secured to said front wall 2 walls of chambers 3, 4, extending into the boiler. I have here shown both upper and lower chambers, there being only a single lower chamber 3, which is almost of the full width 30 of the boiler, being spaced from the sides, bottom and back of the boiler about one or one and one-half inches, and two upper chambers 4, similarly spaced from the sides and back of the boiler and from each other. 35 The chambers 3, 4 are preferably formed with rounded edges 6 at the bottom. Besides being secured to the front wall 2, the lower chamber 3 is additionally supported by legs 7 upon the bottom of the boiler, and 40 the upper chambers 4 are supported by legs 8 upon the top of the chamber 3. The walls of these chambers are preferably formed of copper on account of its great thermal conductivity.

45 Into said chambers are fitted removable cooking vessels 9, 10, preferably of copper or aluminum, and of such shape that their bottoms, sides and rear ends fit snugly against the corresponding walls of the 50 chambers, so that the vessels will be heated by direct radiation from the chamber walls. The front ends of the cooking vessels are, however, spaced from the front ends of the chambers, which latter ends are closed by 55 doors 11, hinged at the bottom, as shown at

12, to the front wall of the boiler, and each carrying a revoluble handle 13, to which is attached a cross bar 14, the ends of which are pivotally attached to bolts 16 which engage keepers 17 upon the front wall 2 adjacent to the marginal portions of the doors. By means of said bolts said doors can be closed against the front wall of the boiler at both their vertical edges. To the front wall immediately below the several doors 60 are riveted angle irons 18, upon which the doors can rest in a horizontal position when open so as to form supports for the cooking vessels.

The boiler is closed at the top by a cover 70 19, having flanges 21 fitting closely within the upper edges of the walls of the boiler, and secured thereto by hinged clamp bolts 22 and thumb nuts 23 thereon. It is provided with handles 24 by which it may be 75 raised and with a filling opening 26 closed by a screw plug 27. It is also provided with a safety valve 28 for permitting the escape of steam from the boiler, when said pressure becomes too high for safety, said steam 80 escaping by a flexible tube 29 to any distant point.

It may be found desirable to baste meat which is being cooked in a cooking vessel. For this purpose the cooking vessel 3 is 85 formed at its front end with a hole 31, closed by a valve 32, having a stem 33 slidably in a vertical guideway 34 secured to the front end of the cooking vessel, said stem being depressed by a spring 36 coiled around the 90 stem and compressed between the upper end of the guideway and a collar 37 secured upon the stem. Said stem is bent at right angles, and extends through a vertical slot 38 in the front end of the cooking vessel, 95 and its extreme outer end is formed into a knob or handle 39 by which the valve can be raised. When the valve is provided, the top of the cooking vessel has extending thereacross a dish-shaped cover 41 having 100 therethrough numerous minute perforations 42 and a handle 43 by which it may be lifted from off the cooking vessel. On drawing out the cooking vessel into the position, for instance, shown in Fig. 4, the 105 juices of the meat can be allowed to flow outwardly through the hole 31, and can then be poured into the concaved cover 41, and allowed to drip slowly over the meat in the cooking vessel.

The position of the doors through which the cooking vessels are withdrawn is very advantageous because in that position the cook scarcely notices the heat of the boiler 5 when opening the door to draw out the cooking vessel, whereas if the cooking vessel had to be withdrawn through the top of the boiler, the cook would be much inconvenienced by the heat rising therefrom.

10 It will be seen that with this improved cooker, the steam is confined within the vessels and does not escape into the chambers, and the edibles are at no time subjected to a temperature much higher than boiling 15 point, since the construction of the boiler does not permit it to withstand a pressure very much greater than atmospheric, and the safety valve is therefore regulated accordingly. When cooked at this temperature, for a sufficient length of time, it is found that meats and other edibles better retain their juices, flavor, and are much more tender than when subjected to a high degree of heat. Moreover, foods cooked by 20 this method keep much longer.

Any number of chickens or fowl of any kind, can be perfectly cooked at the same time, either whole or in parts. In either case, the juices which accumulate in the bottom 25 of the cooking vessel can be withdrawn at intervals and poured into the cover or baster, from which they drop slowly on the upper portion of the food being cooked, thereby moistening it and rendering its flavor uniform throughout. When it is desired to stew or fricassee chickens or other fowl the juices may be withdrawn and a gravy made therefrom and poured over the chicken or fowl. The food can be served direct 30 from the cooking vessel, and can be retained warm therein until ready to serve by keeping the water in the boiler moderately hot.

Potatoes can be cooked either whole or in pieces, and can be mashed in the usual manner by pouring over them milk or cream.

Green corn can be cooked on or off the cob. Peaches, apples, pears, plums and other fruits can be cooked either whole or in pieces. Strawberries and other berries cooked in this manner retain their original shape and appearance intact, and not cooked more or less into shreds, as would be the case if cooked in water.

55 Hams and shoulders can be cooked either with the bone or without it. In case the bone is removed, it is replaced by a small quantity of gelatin and sugar, which have the effect of knitting or binding the meat together in the process of cooking, so that it does not fall apart when sliced. The ham is then pressed, shaped and tied up, ready for cooking. By this arrangement the ham retains its juices and aroma and is of a 60 quality superior to that of one cooked by

the system in which the hams are pressed in shape during the process of cooking by applying a presser plate by means of set screws, since by the latter method too much pressure may be applied, as the pressure is applied merely by guess work. In such case, the juices or essence of the ham is forced out and it is rendered practically tasteless.

I claim:—

1. In a cooker, the combination of a boiler 75 having an opening in one wall thereof, a door movably secured to said wall and closing said opening, means for filling said boiler with water, a chamber extending into said boiler and closed except at said opening 80 and the walls of which are secured to said wall around said opening, and a cooking vessel movable into said chamber through said opening, said vessel fitting snugly within the chamber and with the walls of the 85 vessel contacting with the chamber walls, the wall of the chamber forming a closure for the vessel.

2. In a cooker, the combination of a boiler having an opening in one wall thereof, a 90 safety valve connected with the said boiler, a door movably secured to said wall and closing said opening, means for filling said boiler with water, a chamber extending into said boiler and closed except at said opening 95 and the walls of which are secured to said boiler wall around said opening, and a cooking vessel movable into said chamber through said opening, said vessel fitting snugly within the chamber with the walls of the vessel 100 contacting with the chamber walls, one wall of the chamber coöperating with the vessel to form a closure therefor.

3. In a cooker, the combination of a boiler having an opening in one wall thereof, a 105 removable cover for closing the top of said boiler, means for securing the cover tightly to the top of the boiler, a door movably secured to said wall and closing said opening, means for supplying said boiler with water, 110 a chamber extending into said boiler surrounding the opening and closed except at said opening, and a cooking vessel movable into said chamber through said opening, said vessel fitting snugly in said chamber with the vessel walls contacting with the chamber walls.

4. In a cooker, the combination of a boiler having an opening in one wall thereof, a door movably secured to said wall and closing said opening, means for supplying said boiler with water, a chamber extending into said boiler and surrounding the said opening, a cooking vessel movable into said chamber through said opening, said cooking vessel fitting snugly in the chamber with the walls of the vessel contacting the walls of the chamber and having at its front end a hole for draining liquids therefrom, a valve for closing said hole, and a perforated 130

concave cover for basting the food being cooked.

5. In a cooker, the combination of a boiler embodying an open chamber and a closed 5 surrounding water space, a closure for the said opening, means for filling the space with water, the walls of the chamber being formed of metal of high thermo-conductivity, and a vessel adapted to be placed 10 within the said chamber and to fit snugly therein with the walls of the vessel contacting with the walls of the chamber, one of the walls of the chamber hermetically closing the vessel.
15. 6. In a cooker, the combination of a boiler embodying an open chamber and a closed surrounding water space, a closure for the said opening, means for filling the space with water, the walls of the chamber being 20 formed of metal of high thermo-conductivity, a vessel adapted to be placed within the said chamber and to fit snugly therein with the walls of the vessel contacting with the walls of the chamber, and a reticulated 25 member extending across the top of the vessel.

7. In a cooker, the combination of a boiler having an opening in the side wall thereof, a door for closing said opening, means for 30 filling said boiler with water, a chamber, the walls of which are formed of metal of high thermo-conductivity, extending into said boiler and surrounding said opening, and a vessel movable into and snugly fitting said 35 opening, said vessel being of a size to sub-

stantially fill the chamber, so that the walls of the vessel will contact with the walls of the chamber, one of the walls of the chamber constituting a closure for the vessel.

8. In a cooker, the combination of a boiler 40 having an opening in one wall thereof, a chamber extending into the boiler, said chamber surrounding the said opening and being closed to the interior of the boiler, means whereby water may be supplied to 45 the boiler exterior of the chamber, a cooking vessel movable into the chamber through said opening, said vessel fitting snugly within the chamber so that the walls of the vessel will contact with the chamber walls, and 50 a closure for the entrance opening of the said chamber.

9. In a cooker, the combination of a boiler having an opening in one wall thereof, a chamber extending into the boiler, said 55 chamber surrounding the said opening and being closed to the interior of the boiler, means whereby water may be supplied to the boiler exterior of the chamber, a cooking vessel movable into the chamber through 60 said opening, said vessel fitting snugly within the chamber so that the walls of the vessel will contact with the chamber walls, and a door for closing the entrance opening of the chamber, said door being hingedly connected with the boiler wall and adapted 65 when opened to form a support for the said cooking vessel.

ALFRED M. DEMUTH.
